ROLLER SKATE

George A. L. Draws, Milwaukee, Wis.

Application March 22, 1934, Serial No. 716,787

5 Claims. (Cl. 208—173)

This invention appertains to roller skates either of the rink or sidewalk type.

One of the primary objects of my invention is to provide a roller skate having a novel form of 5 brake mechanism on the wheels thereof, whereby persons can quickly and conveniently stop without danger of marring the surface on which they are skating.

Another salient object of my invention is to 10 provide novel means on the skate for preventing retrograde movement of the rollers, so that persons will be effectively prevented from rolling backwards down an inclined surface.

A further important object of my invention is 15 to provide a novel unit for a roller skate, embodying a brake drum connected and rotatable with the wheels of the skate, and a brake shoe pivotally carried by the skate body for braking engagement with the drum when pressure is 20 applied by the foot to a ground roller carried by the brake shoe, the drum and skate body being provided with a novel ratchet mechanism to prevent the reverse or backward movement of the wheels.

25 A further object of my invention is to provide a novel means for incorporating the unit in a skate, whereby repairs and replacements can be conveniently and quickly made.

A still further object of my invention is to 30 provide an improved skate of the above character, which will be durable and efficient in use, one that will be simple and easy to manufacture, and one which can be placed upon the market at a reasonable cost.

35 With these and other objects in view the invention consists in the novel construction, arrangement and formation of parts, as will be hereinafter more specifically described, claimed, and illustrated in the accompanying drawing, in 40 which drawing:

Figure 1 is a side elevation of a roller skate equipped with my invention, parts of the view being shown broken away and in section to illustrate structural details.

45 Figure 2 is a transverse, sectional view through the skate, showing my invention applied.

Referring to the drawing in detail, wherein 50 similar reference characters designate corresponding parts throughout the several views, the letter A generally indicates a roller skate which comprises a foot plate 5 which can be of any preferred or conventional structure. The forward end of the foot plate 5 carries the front wheels 6, and this front wheel structure can be of any 55 desired type or character. The usual toe clamps

7 are carried by the front of the skate. The rear part of the foot plate is also provided with the usual heel seat for carrying the angle strap 8. The heel part of the foot plate 5 can carry depending brackets 9 for supporting the rear axle 10 on which is rotatably mounted the rear wheels 11 and 12.

In the present instance the wheels 11 and 12 include companion hub plates 13 and 14 for receiving therebetween a tire 15 which can be 60 formed of rubber. Disposed between the hub plates 13 and 14 are ball bearing races 16 for the ball bearings 17, which ride on cones 18 disposed upon the axle. Inner hub plates 14 65 on each wheel carry inwardly directed, axially disposed threaded hub sleeves 19, and a brake drum or hub spool 20 of annular form is arranged between the inner hub plates. The bore of the hub spool or brake drum is internally disposed for receiving the threaded hub sleeves 19. The outer face of the spool or drum 20 have attached thereto any preferred type of 70 renewable brake line 21, which can be formed of asbestos, if desired.

During the assembling of the rear rollers 11 75 and 12 with the brake drum, ratchet wheels 22 and 23 are clamped between the inner hub plates 14 and the drum, and if desired the ratchet wheels can be rigidly secured to the 80 drum by means of fastening screws. The ratchet wheels 22 and 23 extend beyond the periphery of the spool or drum and form a housing for the 85 brake lining 21.

Rockably mounted on the skate body or foot- 90 plate 5 is an arcuate brake shoe 25, which extends between the ratchet wheels 22 and 23, and this brake shoe follows the curvature of the drum. Formed on the rear end of the shoe 25 is an arm 26, which carries an axle 27 on which 95 is rotatably mounted a small, round roller 28. The upper end of the arcuate brake shoe 25 has formed thereon a forwardly and angularly extending leg or stop lug 29, for a purpose which 100 will be later set forth.

A contractile coil spring 30 is connected to the 105 extreme outer end of the lug 29 and to the foot-plate, and normally tends to move the brake shoe 25 away from the brake drum and the roller 28 into engagement with the ground. The downward swinging movement of the brake shoe and roller 28 can be limited by means of a screw 31, which is adjustably carried by the foot-plate. Obviously by adjusting the screw 31, the position of the roller 28 with relation to the 110 ground can be accurately determined.

Pivottally carried by the rear end of the foot plate is a depending ratchet dog 32 having a relatively broad, inwardly directed, transversely extending tooth 33 for engaging the periphery 5 of the ratchet wheels 22 and 23. The dog is normally urged towards the teeth of the ratchet wheels by gravity, and by referring to Figure 1 of the drawing, it can be seen that when the 10 skate is moving in a forward direction, the wheels will be turning in a counter-clockwise direction, and the teeth of the ratchet wheels will catch on the dog 32, thereby preventing further movement of the wheels.

I prefer to mount the shoe 25 and dog 32 in 15 a special manner on the skate, and hence I provide a removable heel-plate 34 for the foot-plate 5 of the skate, and the foot-plate at its rear end is provided with an opening for receiving the heel-plate. The heel plate can be 20 removably held in position by the use of suitable screws. The lower face of the heel-plate 34 carries depending brackets 35 and 36.

During forward movement of the skate, a person can conveniently and quickly stop his movement by pressing downwardly and backwardly 25 on the roller 28, and obviously the brake shoe 25 will be forced into engagement with the brake drum. Obviously, by governing the force of pressure on the roller 28, the quickness of the 30 braking action can be regulated.

In assembling the skate, the rear wheels and the brake drum are assembled as a single unit, and are placed between the brackets 9, after which the axle 10 is slipped through the brackets, bearing cones, and drum. A spaced sleeve 35 24 can be placed on the axle 17 between the cones 18, if desired.

From the foregoing description it can be seen that I have provided a roller skate, in which a 40 novel braking unit, and means for preventing backward movement of the rollers, are provided.

Changes in details may be made without departing from the spirit or scope of this invention, but what I claim as new is:—

1. In a roller skate, a foot-plate, an axle, a pair of rollers rotatably mounted on the axle, a brake drum disposed between and rigidly connected to the rollers, and a pivot brake shoe 50 movably mounted toward and away from the drum, and a ground roller carried by the shoe.

2. In a roller skate, a foot-plate, an axle, a pair of rollers rotatably mounted on the axle, a brake drum disposed between and rigidly connected to the rollers, a pivot brake shoe movably mounted toward and away from the drum, a ground roller carried by the shoe, and resilient means normally urging the shoe away from the drum and roller toward the ground. 80

3. In a roller skate, a foot-plate, an axle carried by the foot-plate, a pair of rollers rotatably mounted on the axle, a brake drum mounted on the axle and disposed between the rollers, means rigidly connecting the drum with the rollers, a brake lining on said drum, an arcuate brake shoe pivotally mounted at its upper end on the foot-plate, said shoe encircling the lower part of the brake lining and drum, a downwardly extending arm on the lower end of the shoe, a roller carried by the arm, resilient means normally urging the shoe away from the drum and the roller in engagement with the ground, and adjustable means for limiting outward movement of the shoe on influence of said spring. 85

4. In a roller skate, a foot-plate, an axle carried by the foot-plate, a pair of wheels rotatably mounted on the axle, a hub spool disposed between the wheels, ratchet wheels secured between the hub spool and the wheels, the wheels, hub spool and ratchet wheels rotating as a unit, a pivoted pawl carried by the foot-plate for engaging the teeth of the ratchet wheels, a brake lining on the spool, and a pivoted brake shoe partially encircling the spool having a ground-engaging roller. 100

5. In a roller skate, a foot-plate, depending 110 brackets on the foot-plate, an axle removably associated with the brackets, ground wheels rotatably mounted on the axle having inwardly directed, axially disposed threaded hub sleeves, a brake drum having an internally threaded bore 115 receiving said sleeves, ratchet wheels clamped between the brake drum and ground wheels, a brake shoe pivotally secured to the heel plate having a ground-engaging roller on its lower end and partially encircling the drum, and a 120 pivoted pawl carried by the foot-plate for engaging the teeth of the ratchet wheels.
